[57] CLAIM

The ornamental design for a RF scan gun holder, as shown and described.

DESCRIPTION

FIG. 1 is a top plan view of the RF scan gun holder of the present design;

FIG. 2 is a first side elevational view thereof;

FIG. 3 is a second side elevational view thereof;

FIG. 4 is a bottom plan view thereof; and,

FIG. 5 is a perspective view thereof with a RF scan gun shown in broken lines, the broken line drawing is for illustrative purposes only and forms no part of the claimed design.
